UNITED STATES PATENT OFFICE

2,070,529

MARKSMANSHIP PRACTICING DEVICE

William P. Falkenberg, Chicago, Ill., assignor to
Raylite Rifle Range Company, Chicago, Ill., a
corporation of Oklahoma

Original application February 15, 1936, Serial No.
64,042. Divided and this application October
7, 1936, Serial No. 104,485

7 Claims. (Cl. 124—15)

My invention relates to improvements in marksmanship devices and has for one object to provide a new and improved form of movable target.

Another object is to provide a new and improved form of marksmanship device wherein a light sensitive cell is used as part of the target and means are provided for projecting a timed, very short flash of light from a gun upon the target to simulate the action of a bullet.

Another object is to provide a new and improved form of light gun for projecting a flash of light upon a target.

Another object is to provide means whereby a single light sensitive cell may be used in connection with a plurality of movable targets to cause each target successively to respond if a light flash is projected upon it while it is located in the aiming area.

Other objects will appear from time to time throughout the specification and claims.

The present application is a division of my co-pending application Serial No. 64,042, filed on February 15, 1936.

My invention is illustrated more or less diagrammatically in the accompanying drawings wherein:

Figure 1 is a front elevation of the target mechanism;

Figure 2 is a plan view of the device shown in Figure 1;

Figure 3 is a side elevation of the gun and part of the target mechanism, with parts in section;

Figure 4 is a longitudinal section of a portion of the gun;

Figure 5 is a section similar to Figure 4 showing the trigger in a different position;

Figure 6 is a section along the line 6—6 of Figure 5;

Figure 7 is a section along the line 7—7 of Figure 4;

Figure 8 is a plan view of a slightly different target mechanism;

Figure 9 is a section along the line 9—9 of Figure 8;

Figure 10 is a section along a line similar to Figure 4, showing a slightly modified form;

Figure 11 is a diagrammatic wiring diagram; and

Figure 12 is a perspective view of the device in operation.

Like parts are indicated by like characters throughout the specification and drawings.

1 is a supporting base. Projecting upwardly from it is an A-frame 2, terminating in a bearing

3, which supports a shaft 4 having a pulley 5. 6 is a speed reduction gear having a pulley 7. An endless belt 8, travels over the pulleys 5 and 7. The speed reduction gear 6 is mounted on the base 1, as is a motor 9 which provides power to operate the speed reduction gear. 10, 11 are curvilinear tracks supported on uprights 12, projecting upwardly from the base 1. The upper portion of the curvilinear tracks may be provided with horizontal sections 13, 14, as indicated, 15 which carry on their upper surfaces insulated tracks 15, 16. Projecting radially from the shaft 4 are sleeves 17, 18 in which are slidable extension sleeves 19 and 20. Springs 21 are enclosed within the pairs of sleeves 17, 18 and 19, 20. 17

Mounted on the outer ends of the sleeves 19, 20 are carriages 22, 23 having rollers 24 adapted to travel along the tracks 10, 11, being thrust against the inner peripheries thereof by the springs 21. Each carriage supports a light sensitive cell 25, 26 and pivoted on each carriage in front of the light sensitive cell is an apertured duck or similar target 26, 27. These aiming objects are adapted normally to remain in a plane perpendicular to the axis of rotation and in the preferred form since the axis of rotation is generally parallel with the line of sight, the aiming objects remain normally in a position perpendicular to the line of sight. This whole apparatus, that is, the duck, the cell, the carriage, and the associated mechanism, comprises a target and target drop assembly. 27

Downwardly depending from the horizontal portion 13 of the track 10 is a bracket 30. This bracket carries a solenoid 31. Associated with the solenoid 31 is an armature 32, pivoted on the bracket 30 and having an upwardly extending arm 33, held as shown in Figure 3 against clockwise rotation by the spring 34. This arm supports a target drop bar 35, which extends parallel with and adjacent the track portion 13, 35 beneath and out of contact with the carriages 22 and 23 as they travel along the track. Extending downwardly from the targets 26, 27 are fingers 36, there being one for each target. These fingers extend down below the bar 35, and being located forwardly of the carriage, they are free to rotate without interference with it. When the solenoid 31 is energized, it pulls the armature 32 in a clockwise direction, causing the bar 35 to strike the finger 36 to knock the duck or other target over in the direction toward the shooter. 36

When the motor is operated, the targets travel round and round along their track in a clockwise direction, as shown in Figure 1, being sup-

ported and driven by the radial arms. These radial arms are assisted in their work by the carriage which travels along the track, and thus the target is constrained to a rectilinear motion for a portion of its travel. If the track were omitted, or if the track were curvilinear throughout, the duck or target would have a circular path in the line of sight and under some circumstances this is desirable, though under other circumstances it is desirable to have the target constrained to a horizontal line of travel. By changing the contour of the track, it is possible to change or control the line of travel of the target while it is within the aiming area. For instance, by inclining the horizontal part 13 of the track upwardly, the ducks could be made to appear to take a rising flight. Other changes in this arrangement are, of course, obvious.

Referring now to the gun as illustrated specifically in Figures 3 to 7, 40 is the gun stock, 41 the barrel, 42 an electric cable passing out through the gun stock through the pistol grip 43 and this cable forms the center connection between the gun and the rest of the mechanism 25 so that the gun may be manipulated by the shooter just as if there were no connection between it and the mechanism.

44 is a hollow receiver, 45 the fore end associated with the receiver and barrel, 46 the trigger, 30 guard and 47 the trigger. The trigger is pivoted within the receiver on a pivot screw 48, and is held in the forward position by the spring 49. 50 is a tension member extending from the trigger over the pulley 51 to the lever arm 52 of an 35 iris diaphragm shutter 53 of the sort used in connection with cameras and the like. 54 is an electric light bulb mounted on a bracket 55 in the receiver behind the shutter. 56 is a lens in the barrel adjacent the bridge; 57 a lens in the barrel 40 adjacent the muzzle. 58 is a rear sight and 59 the front sight.

The arrangement is such that when current is on the light, if the trigger is pulled the shutter will suddenly open and close, allowing a short timed almost instantaneous flash of light to be projected through the shutter and into the barrel, being there condensed and controlled by the lens so as to project a flash of light upon the light sensitive cell associated with the target assembly if the piece is properly aimed. The duration of the flash of light must be great enough so that the current generated in the light sensitive cell will be sufficient in force and duration so that the amplifying system may go into operation. 55 At the same time, the flash of light must be so short that the operator cannot swing the gun after the light is on to follow up the target.

60 is a bracket on the side wall of the receiver. It serves as an anchorage for the spring 49 and 60 carries an insulating block 61, in which are mounted flexible switch points 62, 63, insulated one from another and associated with conductors 173, 177, which extend out through the cable 42. 66 is a dog pivoted on the trigger, yieldingly held against counter clockwise rotation with respect thereto by the spring 67.

Starting with the parts shown in the position of Figure 4, the operator pulls the trigger. That, in the well-known manner, causes the shutter to open and shut to flash a light toward the target. The trigger is then in the position shown in Figure 5, the dog having moved sufficiently in a counter clockwise direction to permit it to assume the full line position shown in Figure 5, without 70 affecting the switch points 63, 62. As soon as the

shooter releases his hold on the trigger, the spring 68 returns it to the position shown in Figure 4, but as it does so, the dog 66 depresses the spring point 63 to close a circuit between it and the spring point 62, the purpose of which will hereinafter appear.

Associated with the iris diaphragm shutter is a bracket 68 having insulating block 69 in which are mounted the switch points 68, 69 associated with conductors 173, 179, which also pass out 10 through the cable 42. Whenever the shutter is operated, the pin 73 associated therewith engages the switch point 68 and closes a circuit between 68 and 69, the purpose of which will hereinafter appear. It will be understood that 15 the conductors 174, 175 to furnish current for the lamp 54 also pass out through the cable 42.

By this arrangement it will be noted that the light is energized while the gun is being used. Ordinarily the gun is used with a great deal of 20 rapidity, ten shots being made in a very short length of time, and there will be no objection to that. Under some circumstances it may happen that the user will stand the gun in its rack for a while and perhaps not finish its whole number of shots and this would leave the light burning indefinitely, which would be undesirable. Therefore, the device shown in Figure 10 is provided with a mercury switch 74, set in an inclined position as indicated so that when the gun is horizontal for use a circuit will be closed. If the gun is laid down or is stood up or is held in some other position, the mercury switch will break the circuit through the light only, thus protecting the light and gun from overheating.

In the modified form shown in Figures 8 and 9, the mechanism and parts are all the same except that the light sensitive cell is omitted. In place of it, is an inclined curved mirror 80 adapted to be masked by the target and to receive a 40 flash of light which has been properly directed on the target to pass through the aperture therein. Instead of having a separate photo-electric cell for each target, a photo or light sensitive cell 81 is supported in the cabinet 82 which encloses the 45 target mechanism and this light sensitive cell is associated with a curved reflector 83. The angles and shapes of the reflectors 80 and 83 are such that whenever a beam of light passes through the aperture in the target, so long as the target 50 is in its effective or shooting area, that beam of light will be reflected from the target mirror to the light cell mirror and there directed upon the light sensitive cell.

It will be understood that the purpose of the 55 light sensitive cell in each case is to generate a sufficient current when a flash of light impinges upon it, such that the current can be amplified or controlled or made use of to cause the operation of the solenoid and drop the target, thereby indicating to the user that a hit has been made. The mechanism by which the signal or the light sensitive cell is picked up, amplified and made use of forms no part of my present invention and a large number of suitable circuits and apparatus 60 for accomplishing this purpose are available and well-known on the market.

The purpose of the switch associated with the iris shutter is by electrical means to cause the operation of what is known in the trade as a 70 thud device which has for its purpose to make a sound simulating the impact of a bullet on a target. This explosion or sound ought to come, of course immediately after the trigger is pulled and the light flash or light bullet is projected.

and hence is connected up with the shutter which controls the time at which the light is flashed. The switch mechanism associated with the trigger itself is for the purpose of operating a counting mechanism and cut-off switch so as to measure or meter the number of times the trigger is pulled, that is, the number of times shots are fired. Devices of this kind are ordinarily used in connection with coin control mechanisms and only a certain predetermined number of shots may be fired for one coin, hence it is necessary to have some means associated with the trigger to control the operation of a suitable shot counting mechanism.

15 Referring now to the wiring diagram shown in Figure 11, 101 indicates a shooting stand. 102 is a coin controlled slide which, when a coin is inserted and the slide is pushed in, operates the interior mechanism. It will be understood that, 20 depending upon the design of the coin slide, it either cannot be pushed in or if it does produces no result unless the coin is present, and that it automatically withdraws after the coin has once been used to operate. When the slide has been 25 pushed in, a circuit is closed at the switch points 103 and also a circuit is closed by the time switch 104. This time switch 104 remains operative for a predetermined period of time and thereafter opens the circuit. When the circuits are closed 30 at 103 and 104, a current passes from the battery along the conductor 105, through the switch points 103, conductors 106 and 107, through the switch 104, conductor 108, through the solenoid 109, conductors 110, 111 through the reset coil 112, conductors 113 and 114, and thence returned to the battery. This circuit closes three circuits at 115, 116 and 117, because the solenoid moves the switch members into the closed position. It also pulls the armature 118 in a clockwise direction against the spring 119 and through a shunt circuit from conductor 110, through conductor 120 through reset magnet 121, conductor 122, back to 114, pulls the armature 123 in a clockwise direction against the spring 124. The movement of the armature 118 inaugurates the operation of the shot counter to control the number of shots which may be fired. The movement of the armature 123 inaugurates operation of the hit counter to indicate the number of hits that 50 have been made.

When the armature 118 is moved in a clockwise direction, the latch 125 is disengaged from the ratchet wheel 126 and the spring 127 rotates that wheel in a counter clockwise direction, moving the 55 finger 128 along the quadrant 129 into the dotted line position. The latch 130 on the armature 131 associated with the actuating magnet 132 is at that time in the inoperative position.

With reference to the hit counting mechanism, the action is the same, though in the drawings it is shown as if there were no indication of hits to start with from the preceding use, so all that the coil 121 does is to pull the armature 123 back to maintain the latch 133 out of contact with the ratchet 134, the spring 135 holding the conductor arm 136 against the stop 137 in the starting position.

Because the circuit is closed only temporarily at 103, some means are needed to lock the circuits closed at 115, 116 and 117. These means are as follows:

Under these circumstances a current travels through the conductor 139 from the ordinary house wiring power circuit at 110 volts to the 75 conductor 140, through 117, conductors 141, 142,

to the transformer 143, thence through the conductors 144, 145, 146 to return to the house lighting circuit through conductor 147. The motor 9 is supplied with power by means of a circuit leading from 141 through conductor 148, conductor 149, conductor 149a to conductor 145 so that the motor and the transformer are in parallel. Also, the conductor 150 leading from the conductor 148 through the transformer 151 back to the conductor 146 furnishes 6 volt alternating current to operate the other parts of the mechanism as will hereinafter appear.

A holding circuit is at the same time closed leading from the 30 volt power source associated with the transformer 143 through conductor 152 to the arm 128 thence through the segment 129, conductor 153, to conductor 120, conductor 110, through the solenoid coil 109, conductor 108, the time switch 104, conductor 107, conductor 154, back to the power source 155. This provides a 20 locking circuit to maintain solenoid 109 energized and keep the circuits closed at 115, 116 and 117. The apparatus is now ready for the user to shoot because the hit indicator and the shot counter are in the starting position and the motor is driving 25 the targets.

The operator then aims at the target and pulls the trigger. When he pulls the trigger, a circuit is closed at 68, 69, in response to the operation of the shutter. When this is done, the 30 current travels from the transformer 151, through conductor 156, switch 115, conductor 157, conductor 158, to switch point 69, thence from 68 through conductor 159, through a solenoid coil 160, which moves the core 170 to the left striking the hammer 171 against an anvil 172 to make a thud or sound of explosion. During this operation, current also passes from the transformer coil through conductor 156, 115, 157, conductor 173, conductor 174 through the light 54, 40 conductor 175, 176, back to the transformer coil.

When the operator releases the trigger, a circuit is closed at 62, 63 in the gun. Under these circumstances, current travels from 113, 62, 63, 177, actuating coils 132, conductor 178 to 176. 45 When the coil 132 is energized the armature 131 is pulled to the right and the conductor finger 128 is moved one step in a clockwise direction. Each time this happens this arm is moved another step until after preferably ten shots 50 it runs off the quadrant 129, breaks the connection, releases the locking circuit, and the whole mechanism returns to its inoperative position with the motor at rest and the transformer dead.

In the event that when the shooter pulled the trigger the gun was properly aimed, a current is generated in the light sensitive cell 26 and current passes from the cell through the conductor 179, contact finger 180, conductor rail 18, conductor 181 to the amplifying system, thence from that system through conductor 182, rail 16, contact finger 183, conductor 184, back to the light sensitive cell. The electric impulse from the light sensitive cell which is amplified by the 65 amplifying unit exerts a pull on the solenoid plunger 185 to close a circuit at 186. When this is done, current passes from the 110 volt line at 139 through conductor 140, switch 117, conductor 187, switch 116, conductor 188, switch 70 186, conductor 189 and conductor 190, coil 31 to knock the target down, thence through conductor 191, 192 back to the other side of the 110 volt A. C. house line. At the same time, current passes through the shunt transformer coil 75

4 at 193 in parallel with the coil 31 to ring the bell 194 once for each hit.

The power unit which amplifies the signal or impulse from the light sensitive cell is constantly maintained in an energized condition by 110 volt current from the conductor 139 through conductor 195, transformer coil 196, conductor 197 and back to the main line at 147.

When a hit is made, it is indicated by illuminating a light. Since ten shots can be fired, ten hits are possible and so there are ten lights, one for each hit and each hit illuminates the light next in the series. The function of this mechanism is as follows: When the solenoid 135 is energized as above indicated and the circuit is closed at 186, current passes from 189 through 198 through the transformer 199, conductor 200, back to the main line through 144, 145, 186 and 147. This generates a current in the circuit 201 to energize the coil 202, move the armature 203 in a clockwise direction against the tension of the spring 204, and rotate the ratchet wheel 134 against the tension of the spring 135 one notch. This brings the arm 136 in contact with the terminal 205 and a circuit is closed through 189, 140, switch 117, conductor 141, 142, through the hand switch 206, and conductors 207 to the finger 136, and light No. 1 is illuminated.

For each successive hit, the same thing happens except that the arm 136 moves from point to point illuminating successive numbers, and when the last shot is fired, the light indicating the highest number of hits remains lighted until the mechanism is returned to the starting position, so that during the time when the machine is idle the hits made by the last customer are always shown.

Referring to Fig. 12, 225 is the housing. It is apertured at 226 and the aperture is enclosed by a glass panel 227. Behind it is visible a landscape with the moving target. 228 indicates the series of apertures in the target through which the hits are made visible by illumination of the lights behind the numbers. 229 is an electric cable containing a number of conductors leading from the cabinet 225 to the gunstand 230. 231 is an electric cable leading from the gunstand 230 to the gun 232. 233 is the coin control slot and slide mounted on the gunstand 230. 234 is the upper part of the gun rack and 235 is the lower part. It will be noted that the upper part 234 is slotted so that a gun may be rested in the rack with the butt resting on the bottom 235 and the gun in the open sided slot 234. 236 is an electric conductor leading from the cabinet 225 to a light socket not shown with the house lighting circuit whereby electric current may be supplied to the apparatus.

I claim:

60 1. In a target device, a plurality of movable targets and means for successively bringing them into aiming position, each target comprising an apertured plate and a reflecting mirror mounted for movement therewith, a fixed mirror, and a light sensitive cell associated with the fixed mirror, the relationship between the apertured target plate, the movable mirror and the fixed mirror being such that when a flash of light penetrates the apertured target plate and impinges upon the movable mirror, it will be reflected by it and by the fixed mirror against the light sensitive cell.

2. In a target device, a plurality of movable

targets and means for successively bringing them into aiming position, each target comprising an apertured plate and a reflecting mirror mounted for movement therewith, a fixed mirror, a light sensitive cell associated with the fixed mirror, the relationship between the apertured target plate, the movable mirror and the fixed mirror being such that when a flash of light penetrates the apertured target plate and impinges upon the movable mirror, it will be reflected by it and by the fixed mirror against the light sensitive cell, and means responsive to the activation of the light sensitive cell by such light flash for indicating a hit on the target.

3. In a marksmanship device, a target adapted to move across the line of sight, a carriage upon which the target is mounted, the target including a plate adapted normally to remain in a position perpendicular to the line of sight, electromagnetic means adapted to engage the plate to knock it over, a light sensitive cell associated with the target, and amplifying means interposed between the light sensitive cell and the electromagnetic means whereby a signal resulting from the impingement of the light flash on the cell is amplified and actuates the electromagnetic means.

4. In a target apparatus, a target including a reflecting member, a normally fixed light sensitive cell, adapted to receive light from said reflecting member, signal means, means for actuating said signal means in response to the impingement of a reflected flash of light from said reflecting member upon said cell, and means for imparting movement to said target and reflecting members during its use.

5. In a target apparatus, a target including a reflecting member, a light sensitive cell adapted to receive light from said reflecting member, said light sensitive cell being normally fixed, signal means, means for actuating said signal means in response to the impingement of a reflected flash of light from said reflecting member upon said cell, and means for imparting movement to said target and reflecting member during its use.

6. In a target apparatus, a target including a base and means for moving it, an apertured target member positioned on said base, a reflecting member positioned to the rear of said aperture, a light sensitive cell adapted to receive light from said reflecting member, said light sensitive cell being normally fixed, signal means, and means for actuating said signal means in response to the impingement of a reflected flash of light from said reflecting member on said cell.

7. In a target device, a movable target and means for moving the target through a predetermined path, said target including an apertured plate and a mirror mounted in alignment with said aperture, said mirror and plate mounted for movement as a unit, a fixed mirror, and a light sensitive cell operatively disposed to receive light reflected from the fixed mirror; the relation of the fixed mirror and the movable target being such that when a beam of light penetrates the aperture of the target while moving through a predetermined portion of its path of movement and impinges upon said mirror carried by the target, said light beam is reflected upon the stationary mirror and from thence to the light sensitive cell, and signal means operative in response to energization of the cell.
